4 Claims. (Cl. 66—1.5)

This invention relates to an apparatus for operating a relooping needle by means of a motor, of a crank communicating a reciprocating movement to a flexible wire sliding in a tube and by 5 means of a clutch connecting the crank to the motor practically only when said motor receives energy.

The apparatus according to the invention comprises in particular an elastic member acting on 10 the crank and so disposed that the crank when out of gear is always immediately brought back to its dead centre, opposite the end of the tube on the crank side.

The accompanying drawing shows an embodiment of the apparatus according to the invention, given by way of example.

Fig. 1 is an elevation of the apparatus.

Fig. 2 is a partial end view of same and

Fig. 3 shows in diagram the electrical connections of same.

The apparatus shown consists of a base 1 carrying a bed 2 adapted to rotate in said base around the vertical pivot 3. In the bed is located an electric motor 4 intended to drive a crank 5 carried by a disk 6, the transmission of the movement being effected by means of a band 7 connecting the pulley 8 of the motor to the pulley 9 of the shaft 10. Said shaft rotates in a bearing 11 integral with the bed 2. Said shaft carries 30 one of the parts 12 of a clutch 12, 13, the other part of which is carried by the bearing 14 and carries in its turn the disk 6 and the crank 5.

The axial displacement necessary for operating the clutch 12, 13 is obtained by means of a ring 35 15 operated by the fork 16 of a lever 17 pivoted at 18. Said lever is actuated by the armature 19 of an electro-magnet 20, likewise carried by the bed 2.

To the crank 5 is connected a connecting rod 40 21 acting on a rod 22 guided at 23 and penetrating into a sleeve 24, in which said rod 22 is connected to a flexible wire sliding in a tube 25. A portion of said flexible wire, designated by 26 is visible in Fig. 2.

45 Flexible wire and tube end in needle holder 27 shown in the rest position in Fig. 1. In said position, said holder lies in a sleeve 28 integral with the bed 2 and in particular intended to protect the needle contained by said holder. The holder 50 itself can, for example be of the type described in the patent application 109,656 simultaneously filed and copending herewith, entitled, "Needle holder for a relooping needle".

Finally a spring 29 constantly tries to push the 55 armature 19 out of the electro-magnet, whereas

another spring 30 surrounding the rod 22 and resting on the sleeve 24 pushes the connecting rod 21, so as to try to bring the crank constantly back to its dead centre, opposite the end of the tube 25 on the crank side, and this can also be called the 5 rear dead centre of the crank, as in said position the needle in the needle holder 27 occupies its most remote position.

To use the apparatus described, the needle holder 27 is extracted from the sleeve 28, then it 10 is held in the operative position over the fabric to be relooped. As the arm 31 carrying the guide 23 and the sleeve 24 can rotate with frictional resistance around the axis of the disk 6, between two immovable washers 32, 33, said arm may be 15 inclined into the position best adapted for the work, for example it may be brought into the horizontal position shown in Fig. 2. In said Figure 2, the position 31' in dot and dash line corresponds to the rest position, that is to say to the 20 position shown in Fig. 1.

Then, the motor 4 and the electro-magnet 20 are energized. The motor starts running and the electro-magnet by drawing its armature 19 against the action of the spring 29 causes the 25 connection between the parts 12 and 13 and the immediate rotation of the crank 5, i. e. of the needle which will in the holder effect a reciprocating movement.

To stop the operation, it is only necessary to 30 cut off the current. The motor does not stop immediately by virtue of its inertia, but the needle will stop instantaneously, because the electro-magnet will instantaneously cease to connect the parts 12 and 13. Due to the spring 30, the 35 instantaneous stoppage of the needle will be effected in its most remote position, as the spring 30 will immediately push the crank 5 back to its rear dead centre.

The control of the motor and of the electro-magnet will be effected preferably from a pedal, connected, on the one hand, to the wire net work and on the other hand to the apparatus by means of a tripolar conductor 34. Fig. 3 shows an embodiment of the electrical connection to be adopted. The terminals 35 are connected to the wire net work. One of the poles of said wire net work is directly connected to the motor 4 and to the electro-magnet 20. The other pole is connected to a sliding contact 36 of the pedal, which contains opposite said sliding contact a resistance 37 for the motor and a contact 38 for the electro-magnet. As will be seen, by displacing the sliding contact in the direction of the arrow 39, the motor and the electro-magnet are energized, but 50 55

the further the sliding contact is displaced, the more rapidly the motor runs.

According to the relative positions occupied by the resistance 37 and the contact 38 opposite each other, the motor may be started a little before the electro-magnet is energized or inversely.

The crank 5, as shown, is not fixed on the disk 6. It can rotate on said disk around a centre 40 and under the influence of a lever 41, which the bores 42 permit of immobilizing in different positions. By displacing the lever 41 clock-wise as regards the disk 6 in Fig. 2, the crank 5 is removed from the centre of rotation of the disk. By displacing the lever 41 in the opposite direction, said 15 crank is brought closer to said centre. Said disposition therefore permits of modifying the amplitude of the reciprocating movement which the crank 5 gives to the flexible wire 5, i. e. to the relooping needle.

20 What I claim is:—

1. In an apparatus for operating a relooping needle, an electric motor, a tube, a flexible wire 25 slideable in said tube, a crank for reciprocating said wire, a clutch for operatively connecting the crank to the motor only when said motor is energized and an elastic member acting on the crank to move it to its rear dead center immediately upon its being declutched from the motor.
2. In an apparatus for operating a relooping 30 needle, an electric motor, a tube, a flexible wire slideable in said tube, a crank for reciprocating said wire, a clutch for operatively connecting the

crank to the motor only when said motor is energized, an elastic member acting on the crank to move it to its rear dead center immediately upon its being declutched from the motor, and an arm independent of said crank mounted for pivotal movement about the crank shaft, one end of said tube being connected to said arm to participate in the pivoting movement.

3. In an apparatus for operating a relooping needle, an electric motor, a tube, a flexible wire 10 slideable in said tube, a crank for reciprocating said wire, a clutch for operatively connecting the crank to the motor only when said motor is energized, an elastic member acting on the crank to move it to its rear dead center immediately upon 15 its being declutched from the motor, and an arm independent of said crank mounted for pivotal movement and frictional resistance about the crank shaft, one end of said tube being connected to said arm to participate in the pivoting movement.

4. In an apparatus for operating a relooping needle, an electric motor, a tube, a flexible wire 25 slideable in said tube, a crank for reciprocating said wire, a clutch for operatively connecting the crank to the motor only when said motor is energized, an elastic member acting on the crank, to move it to its rear dead center immediately upon 30 its being declutched from the motor, and means for varying the amplitude of movement of said crank.

BEDRI HUSSEIN GOSTKOWSKI.
